CAR SEAT FOR AN INFANT

Henry O. Gervais, Deerfield, Fla., assignor to Henry Industries Inc., Wilkes Barre, Pa., a corporation of New York

Filed Nov. 2, 1966, Ser. No. 4,523

Term of patent 7 years

(Cl. D15—1)

The figure is a front perspective view of a car seat for an infant showing my design.

The appearance of the back of the car seat is conventional.

I claim:

The ornamental design for a car seat for an infant, substantially as shown and described.
